REFRIGERATOR CAR WITH FAN AND BRINE CIRCULATING SYSTEM

Thore M. Elfving, San Mateo, Calif., assignor to Union Asbestos & Rubber Company, Chicago, Ill., a corporation of Illinois

Application March 30, 1951, Serial No. 218,350

10 Claims. (Cl. 62—24)

1

The present invention relates to railroad refrigerator cars using ice or a mixture of ice and salt as refrigerant. It has for its purpose to provide a refrigerator car, which can maintain a constant low temperature independent of the amount of ice and salt in the ice bunkers and independent of the car being in motion or not.

According to the invention the temperature in the car can be thermostatically regulated as if the car was provided with mechanical refrigeration. Like present refrigerator cars, the lowest temperature obtainable in a car will be dependent upon the temperature of the ice and salt mixture or the refrigerant in the ice bunkers, but in other respects the present invention eliminates many of the weaknesses found in railroad refrigerator cars of the present ice bunker type.

A refrigerator car according to the present invention can use either end ice bunkers or overhead ice bunkers or both. As an example, the invention will be described in connection with the accompanying drawings as applied to a refrigerator car of the end ice bunker type.

In the drawings:

Figure 1 shows a longitudinal section through one-half of a refrigerator car according to the invention, and

Figure 2 shows a cross section view of the car as shown in Figure 1.

In these drawings a conventional refrigerator car is shown as composed of wheels represented by 1, underframe 2, insulated floor 3, insulated end walls 4, insulated side walls 5, and insulated ceiling 6. In said refrigerator car there is also indicated a conventional structural bulkhead 7 forming a space in the end of said car, known to the trade as an end ice bunker 8. The walls of said ice bunker are formed by the car end lining 9, side lining 10, and structural bulkhead 7. The ceiling is formed by the car ceiling 11 and the floor is formed by a floor panel 12, which is provided with a drain 13 through a water seal 14. Also indicated are hatch openings 15 and floor racks 16, all of which are well known.

Inside of said ice bunker there is constructed an ice tank 17 directly connected with the hatch openings 15 in such a way that an air passage 18 is provided over the ice tank around said openings. The ice tank is so arranged as to provide an air space 19 and an air channel 20 between the ice tank and the car structure at both the side and end walls. The ice tank 17 is water tight except for the openings 21 for brine overflow. The ice tank is supported by the structural bulkhead 7 and a cross beam 22. In the ice tank is

2

arranged an ice grate 23, which can be raised in a position indicated by 24 for cleaning. This ice grate should, according to the invention, be tight enough to prevent any ice, salt or other solid objects from entering the brine space 25 under the ice grate. At the center of the car the bottom of the ice tank is provided with a cut off valve 26 for emptying and cleaning the tank.

As seen from the above description the ice tank 17 is surrounded on all sides with air passages through which air can be circulated for cooling by contact with the cold sides of the tank. This offers a considerable cooling capacity which, however, is very much increased by the brine circulating system added to the bunker according to the invention. Such a circulating system can be provided with cooling surfaces large enough to obtain the total cooling capacity needed for a car of this type. The brine is circulated by means of a motor driven pump 27 which takes in the brine through the pipe 28 from the brine space 25 underneath the ice grate. Brine is forced from the pump through a fin pipe heat exchange unit 29 consisting of vertically arranged horizontal pipes provided with fins and located in an air circulation flue 30 adjacent to the structure bulkhead 7 and separated from said bulkhead by a wall or baffle 31 extending from the bottom of the bulkhead members to the top of the uppermost horizontal fin pipe. Above this point the air flue 30 and the space between the structural bulkhead members communicate. The other side of the air flue 30 is formed preferably by a wooden lining 32 which extends from the bottom of the bulkhead members to the fan housing 33. The fin pipes are in series and the brine will gradually raise in temperature when passing through this air cooling system. The brine is brought back to the ice tank through the pipe 34. This pipe conducts the warm brine to the top of the tank between the hatch openings and leads across the tank to the outlet spray pipe 35, from which the brine is sprayed over the ice and salt mixture in the tank. The heated brine melts some of the ice, additional salt is dissolved, and the circulation is repeated.

The air is, according to the invention, circulated around the total cooling system by means of electric fans 36 located in holes 37 in the fan housing 33. The air circulation between the commodity space of the car and the cooling system described above is carried out in the following way: Below the load in the car the air is circulated in the space between the floor deck 38 and the floor rack 16 and is pulled by the fan

into the cooling system at the bottom of the bulkhead. The air flow is divided in three separate ways. One part of the air coming from the commodity will go the shortest way through the air flue 30 passing over the brine circulating coil system. This lowers the temperature of the air before it reaches the upper part of the vertical flue where the fans force it out into the commodity space again. Another portion of the air flow goes between the bulkhead structural members between the ice tank 17 and the wall 31. As this passage of the air does not offer large cooling surfaces the air flow through this area is restricted by a restriction member 39. This member 39 does not prevent air circulation by free convection in case the fans are not operating. The remaining portion of air goes under the ice tank and passes around the remaining three sides of the tank up to the top of the bunker, from there to the fans and out over the load again. All three passages described above offer a certain cooling effect to the car, but it will be shown in the following description that the major portion of the necessary refrigerating capacity will be provided by the brine circulating fin pipe system. This system will maintain the same brine temperature as long as any ice remains in the eutectic brine in the tank. It is therefore capable of maintaining a reasonably constant refrigerating capacity as long as the brine pump and the fans are operating.

As shown in Figure 2 of the drawings, the brine circulating system connected with the ice tank is seen from the car after removing the wall 32. 12 is the floor pan with the drains 13 and water seals 14. The brine circulating pump 27 with the motor 40 and the inlet pipe 28 is located between two bulkhead structural members in an opening in the wall 31 within the bulkhead sections and the air flue 30. The pump is therefore readily accessible from inside the car through an inspection opening in the wall 32. The pump is located underneath the fin pipe system and the whole system will drain itself through the pump and the inlet pipe 28 when the brine in the ice tank is drained off through the cut off valve 26 shown in Figure 1. This automatic draining of the cooling coil system and the pump is very important for the reliable operation of the brine circulation as sedimentation inside the pipe system or inside the pump should be avoided. The heat exchange unit 29 is secured inside the air flue by means of wooden members 41 which are bolted to the bulkhead structural members. These members 41 also serve as stringers for securing the plywood wall 32. In Figure 2 are also shown the fans 36 located in the openings 37 as well as the outlet pipe 34 leading from the fin pipe system to the spray pipe 35 which runs practically the full width of the tank. The upper layer of the ice and salt mixture in the tank is thereby contacted by the comparatively warm brine coming from the cooling coil system.

The refrigeration capacity needed for a heavily insulated low temperature car is usually estimated to be approximately 20,000 B. t. u.'s/hour. As previously stated it is possible in a refrigerated car, according to the present invention, to provide the brine circulating system added to the bunker with cooling surfaces large enough to take care of this needed refrigerating capacity. This is accomplished by using fin pipes and by balancing the brine and air circulation in order that a correspondingly large heat flow takes place from the air to the fin pipe system, and from the

fin pipe system to the brine, and finally to the ice and salt mixture in the ice tank. The refrigerating capacity to the air represented by the surface of the ice tank itself may serve as a margin of safety for extreme conditions. A refrigerator car according to the invention should have the following approximate data as far as the cooling system is concerned:

10 The ice tank capacity should be about the same as for conventional cars of the end bunker type, that is approximately 12,000 pounds of ice plus 30 per cent salt by weight. Because of the 15 ability of the invention to maintain full refrigerating capacity until all the ice is melted this amount of ice will be sufficient for approximately 60 hours of operation. With the above proportions of ice and salt it will be possible to obtain a temperature in the ice tank of about -5 degrees Fahrenheit, which temperature will be maintained in the brine entering the brine pump 20 as long as any ice is left. It is assumed that an average temperature difference of 10 degrees Fahrenheit between the coil system surface and the circulating air in the air flue is obtained and it can also be assumed that the heat transmission coefficient between the fin pipes and the air will be 5 B. t. u.'s/square foot/hour, per degree, F., which corresponds to the air velocity obtained with a fan capacity of 3000 C. F. M. or more. We find then that the cooling surface 30 needed for transferring 20,000 B. t. u.'s per hour is about 400 square feet. Approximately half of this surface is obtained with a fin pipe system as shown in Figure 2 which is composed of 35 $\frac{3}{4}$ " pipes provided with suitable fins.

If a brine temperature rise of 3° F. is allowed during the passage of the brine through the coil system it takes the circulation of 400 gallons of brine per hour to deliver a refrigeration capacity of 10,000 B. t. u.'s which gives a brine velocity 40 inside the pipes of approximately 300 feet per minute. The pump and motor capacity should be chosen according to this requirement. With the above dimensions of the cooling coil system together with the cooling capacity of the tank 45 itself it should be possible to maintain a temperature in the car of 5° F. or lower under all conditions.

50 The brine pumps and the fans, as employed according to the present invention, are driven by electric motors which are connected by the cable 42 with an electric generator driven by an internal combustion engine. Figure 2 shows the electric motor 40 for the brine pump 27, and Figure 1 shows the motor 43 for the fan 36. Figure 1 also shows the engine-generator unit 44 as located on a suspended platform 45 which is hung between the underframe cross tie 46 and the underframe cross beam 47. The engine-generator unit is provided with an intersection door 48 having grills 49 for air circulation. The engine has a fuel tank 50 with a capacity large enough for driving the generator at least 10 days, while the car is in transit across the country. A generator for supplying fan and pump motors, according to the invention, with electricity of a suitable voltage has only to produce between 1 and 2 kilowatts, and an internal combustion engine of 2 to 4 horsepower is sufficient for driving the generator. This engine should be of the air-cooled heavy duty type and provided with a starting battery, starting motor, and an automatic starting control unit for thermostatic operation. A selective thermostatic control 55 placed in a suitable position in the commodity

space of the car controls the starting and stopping of the engine at predetermined maximum and minimum temperatures thereby, through the generator unit, the operation of the brine pump, and the air circulating fans. The cooling system is consequently thermostatically controlled by the temperature inside the refrigerator car. When the thermostat starts the combustion engine and the voltage of the generator is built up so that the brine pump and the fans start operating this will have the same effect on the temperature of the car as the thermostat of a compressor refrigerator or another type of refrigerating unit. By these means an ice bunker car can be set to operate at any temperature above the minimum determined by the temperature of the refrigerant in the ice bunkers. When using ice and salt with an eutectic temperature of about -5° F. the minimum temperature in the car will probably be 2° F. or slightly below. The brine and air circulating system can be placed in operation as soon as the car has been iced, thereby reducing the normal precooling time considerably.

A refrigerator car cooling system, according to the invention, is superior to mechanical refrigeration with a compressor unit in the respect that ice and salt in the ice bunkers offers a source of refrigeration which is available even if the combustion engine or the generator or other mechanical parts of the system should fail. The refrigeration capacity of this system, when the brine pump or the fans are not operating, is small compared with the refrigeration capacity when the cooling coil system is working according to the above description. However, the refrigeration with natural convection of the air is sufficient in most cases to prevent damage to the commodity. The air flow around the bunker system, when the fans are standing still, will be in reverse to the air flow described above. Gravity difference will cause the air to enter the system through the fan holes and flow downwards around the tank between the bulkhead structural members and through the air flue for the fin pipe system. Restrictions in the air passages will have less effect on slow moving air than on forced air and a bunker system, according to the invention, will therefore offer equal refrigeration, when fans and pump are not operating, to ordinary end bunker cars now in general use.

A brine circulating cooling system, according to the invention, can be located or arranged in many different ways. Forced brine circulation combined with forced air circulation makes it possible to arrange the fin pipe cooling system almost anywhere in the car. A vertical fin pipe system similar to that described above may be placed in a wall flue behind the bunker or at the side walls. It is also possible to arrange the brine circulating system along the ceiling of the car, above the loading space and between the bulkheads.

The cooling coil system added to the bunker in order to increase the refrigerator capacity of the car, according to the invention, can also be of the self-circulating type, that is a hermetically sealed heat transfer system using a volatile refrigerant such as ammonia or Freon. In this case a brine pump would not be required, and the engine-generator unit has only to supply electricity to the fan for circulating air around the preferably enlarged surface of the heat absorbing part of such a hermetically sealed circulating system as well as around the ice bunker.

A brine-circulating system for cooling the air

can according to the invention also be of the spray or wet surface type, in which case the brine is pumped from the bottom of the ice tank up to a spray pipe located in a vertical air flue through which air is circulated. After leaving the spray pipe the brine may either fall in small drops through the air or drizzle over preferably corrugated surfaces over which the air is passing while being cooled. The pump brine may be divided in two ways, one part being sprayed over the top layer of ice and salt in the ice tank, the other part passing the air cooling flue back to the bottom or lower part of the ice tank.

The generator used for supplying electric power to the pumps and/or fans used in the cooling system, according to the invention, can also be driven from the wheels of the car in which case the generator has to be provided with a storage battery for operating the pumps and/or fans when the car is standing still. The thermostat has in this alternative only to operate a switch in the electric circuit.

While I have, for the sake of clearness and in order to disclose the invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and all such changes as come within the scope of the appended claims are to be considered as part of this invention.

Having thus described my invention, what I claim and desire to secure by Letters Patent is:

1. In a refrigerated railway car having an insulated lading accommodating space, the combination of an ice and brine accommodating tank mounted within said car at one end and spaced from the top, bottom, end and side walls thereof for free passage of air therearound, a baffle disposed vertically and transversely of said car body and terminating in spaced relation with the floor and ceiling of the car to provide an air passageway adjacent the inward side of said ice tank, a heat exchange unit mounted at the other side of said baffle and within the upper and lower limits thereof, a brine pump for circulating brine from the bottom of said tank through said heat exchange unit and discharging same as a spray at the top of said ice tank, an insulating end wall mounted in inwardly spaced relation with respect to said heat exchange unit which defines the limits of the lading space and provides an air circulating passageway through which air will circulate over said heat exchange unit, said end wall being disposed with its bottom edge in spaced relation with floor of the car and having an aperture located above said heat exchange unit, an electric fan mounted in the aperture in said end wall cooperating relation with said baffle for maintaining a forced circulation of air from the lading space about said ice tank and over said heat exchange unit, and means at the lower edge of said baffle for directing the major portion of the fan circulated air over said heat exchange unit.

2. In a refrigerated railway car having an insulated lading accommodating space, the combination of an ice and brine accommodating tank mounted at one end within said car and spaced from the top, bottom, end and side walls thereof to provide for a free circulation of air

therearound, a vertically disposed baffle extending transversely of said car body and spaced from the floor and ceiling to provide an air passageway adjacent the inner side of said ice tank, a finned pipe heat exchange unit mounted at the side of said baffle remote from said tank, a brine circulating pump for circulating brine from the bottom of said ice tank through said heat exchanger and discharging same as a spray over the ice in said ice tank, a heat insulating end wall mounted within said car body and inwardly with respect to said heat exchange unit to provide a confined space through which air will circulate over the fin pipes of said heat exchange unit, said end wall being disposed in spaced relation with floor of the car and having an aperture above said heat exchange unit, an air circulating fan mounted in cooperating relation with said baffle and the aperture of said end wall for circulating air from the lading space of said car about said ice tank and over said heat exchange unit, and means for regulating the flow of air about said ice tank, the arrangement being such that the major portion of said circulating air will be passed over said heat exchange unit when said fan is operating.

3. In a refrigerated railway car having an insulated lading accommodating space, the combination of an ice and brine accommodating tank mounted within said car at one end and spaced from the top, bottom, end and side walls thereof for free passage of air therearound, a baffle extending transversely of said car body in spaced relation with said tank and spaced from the floor and ceiling of the car to provide an air circulating passageway about said ice tank, an insulating end wall mounted in inwardly spaced relation with respect to said baffle which defines the limits of the lading space and provides an air circulating passageway remote from and independent of the passageway about said ice and brine tank, said insulating end wall being disposed with its bottom edge in spaced relation with floor of the car and having an aperture at its upper edge, an electric fan mounted in the aperture in said end wall, a heat exchange unit mounted in said latter air circulating passageway, a brine pump for circulating brine from the bottom of said tank through said heat exchange unit and discharging same as a spray at the top of said ice tank, and means at the lower edge of said baffle for limiting the flow of fan circulated air about said ice tank when said fan is operating.

4. In a refrigerated railway car having an insulated lading accommodating space, the combination of a bulkhead having an opening at its top communicating with the interior of the car and forming a chamber for an ice and brine accommodating tank at the end of the car, an ice and brine tank mounted within said chamber in spaced relation from the top, bottom and side wall of said chamber for the free passage of air therearound, a vertical wall disposed in inwardly spaced relation with said bulkhead and providing vertical air circulating passageway, a circulating brine heat exchange unit mounted in said air passageway and disposed between the upper and lower limits thereof, a brine circulating pump for maintaining a circulation of brine downwardly through said heat exchange unit and discharging said brine as a spray over the ice in said ice and brine accommodating tank, and means for maintaining a forced circulation of air downwardly through said air circulating passageway and over said heat exchange unit.

5. In a refrigerated railway car having an insulated lading accommodating space, the combination of a bulkhead having an opening at its top communicating with the interior of the car and forming a chamber for an ice and brine accommodating tank at the end of the car, an ice and brine tank mounted within said chamber in spaced relation from the top, bottom and side wall of said chamber for the free passage of air therearound, a vertical wall disposed in inwardly spaced relation with said bulkhead and providing vertical air circulating passageway, a circulating brine heat exchange unit mounted in said air passageway and disposed between the upper and lower limits thereof, a brine circulating pump for maintaining a circulation of brine downwardly through said heat exchange unit and discharging said brine as a spray over the ice in said ice and brine accommodating tank, and means for maintaining a forced circulation of air upwardly through said air circulating passageway from the bottom to the top of said lading space of the car, whereby the air circulating over said heat exchange unit will flow in countercurrent relationship with the brine circulated through said heat exchange.

6. In a refrigerated railway car having an insulated lading accommodating space, the combination of a bulkhead having an opening at its top communicating with the interior of the car and forming a chamber for an ice and brine accommodating tank at the end of the car, an ice and brine tank mounted within said chamber in spaced relation from the top, bottom and side wall of said chamber for the free passage of air therearound, a vertical wall disposed in inwardly spaced relation with said bulkhead and providing vertical air circulating passageway, a circulating brine heat exchange unit mounted in said air passageway and disposed between the upper and lower limits thereof, a brine circulating pump for maintaining a circulation of brine downwardly through said heat exchange unit and discharging said brine as a spray over the ice in said ice and brine accommodating tank, and means for maintaining a forced circulation of air upwardly through said air circulating passageway from the bottom to the top of said lading space of the car, whereby the air circulating over said heat exchange unit will flow in countercurrent relationship with the brine circulated through said heat exchange, said air circulating means being disposed and arranged so as to not interfere with a free convection circulation of air around said ice and brine tank and over said heat exchanger unit when said air circulating means is not in operation.

7. In a refrigerated railway car having an insulated lading accommodating space, the combination of a bulkhead having an aperture at its top communicating with the interior of the car and forming a chamber for an ice and brine accommodating tank at the end of the car, an ice and brine tank mounted within said chamber in spaced relation from the top, bottom and side wall of said chamber for the free passage of air therearound, a vertical wall disposed in spaced relation with said bulkhead and providing narrow air circulating passageway extending throughout the width of the car, a circulating brine heat exchange unit having horizontally extending finned tubes mounted in said air passageway and occupying the space between the sides and the upper and lower limits of said passageway, brine circulating pump for maintaining a high velocity circulation of brine downwardly through said heat exchange unit and discharging said brine as a spray over the ice in said ice and brine accommodating tank, and means for maintaining a forced upward circulation of air through said air circulating passageway, whereby the air circulating through said passageway and over said heat exchange unit will flow in countercurrent relationship with the brine circulated through the finned tubes of said heat exchange unit.

8. In a refrigerated railway car having an insulated lading accommodating space, the combination of a bulkhead open at its top and forming a refrigeration medium accommodating chamber in communication with the interior of the car, a metallic ice and brine tank mounted in said chamber in spaced relation with the top, bottom, end and side walls of the car, a vertical wall extending transversely of said car body in spaced relation with said bulkhead and form-

ing an air passageway throughout the width of the car, a heat exchange unit mounted between said bulkhead and said vertical wall and within the upper and lower limits of said vertical wall, a brine circulating pump having connections for withdrawing brine from the bottom of said ice tank and circulating said brine downward through said heat exchange unit and returning said brine as a spray at the top of said ice and brine tank, said vertical wall being terminated short of the floor of the car and having an aperture above said heat exchange unit, and an electric fan mounted in cooperating relation with said bulkhead and the aperture in said vertical wall for maintaining a forced circulation of air from the lading space of said car about said ice and brine tank and through said vertical air passageway in countercurrent relation with respect to the flow of brine through said heat exchange unit.

8. In a refrigerated railway car having an insulated lading accommodating space, the combination of a bulkhead open at its top and forming a refrigeration medium accommodating chamber in communication with the interior of the car, a metallic ice and brine tank mounted in said chamber in spaced relation with the top, bottom, end and said walls of the car, a vertical wall extending transversely of said car body in spaced relation with said bulkhead and forming an air passageway throughout the width of the car, a heat exchange unit mounted between said bulkhead and said vertical wall and within the upper and lower limits of said vertical wall, a brine circulating pump having connections for withdrawing brine from the bottom of said ice tank and circulating said brine downward through said heat exchange unit and returning said brine as a spray at the top of said ice and brine tank, said vertical wall being terminated short of the floor of the car and having an aperture above said heat exchange unit, and an electric fan mounted in cooperating relation with said bulkhead and the aperture in said vertical wall for maintaining a forced circulation of air from the lading space of said car about said ice and brine tank and through said vertical air passageway in countercurrent relation with respect to the flow of brine through said heat exchange unit, said air circulating means being disposed and arranged so as to not interfere with a free convection circulation of air around said ice and brine tank and over said heat exchanger unit when said air circulating means is not in operation.

9. The improvement in a refrigerated railway car having an ice bunker at one end which comprises, a metallic tank within said bunker and spaced from top, bottom and side walls thereof to permit a free circulation of air thereabout, said metallic tank being charged with an eutectic mixture of ice and salt, a circulating brine heat exchange unit disposed inwardly and

adjacent said metallic tank, a vertical and transversely extending partition at each side of said heat exchange unit forming two paths for the circulation of air from within the lading space of said car, one such circulation being around and about said metallic tank and the other over and about said heat exchange unit, pump means for circulating brine from the bottom of said tank through said heat exchange unit and returning said brine as a spray at the top of said metallic tank, an air circulating fan at the upper end of said spaced vertically disposed and transversely extending partitions, and means whereby a major portion of the fan circulated air will pass over said heat exchange unit when said fan is operating, said means being such that it will not materially interfere with a full and free convection circulation of air around said tank and over said heat exchange unit when said fan is not operating.

10. In a refrigerated railway car having an insulated lading accommodating space, the combination of an ice and brine accommodating tank mounted within said car at one end and spaced from the top, bottom, end and side walls thereof for free passage of air therearound, a bulkhead defining a chamber within which said tank is disposed, said bulkhead having an air passageway at its top communicating with the interior of the car, a heat insulating end wall mounted in inwardly spaced relation with respect to said bulkhead defining the limits of the lading space of the car and providing an air circulating passageway remote from an independent of the passageway about and adjacent said ice and brine tank, said insulating end wall being disposed with its bottom edge in spaced relation with floor of the car and having an aperture at its upper edge, a fan mounted at the aperture in said end wall for maintaining an upward circulation of air through said passageway, a heat exchange unit mounted in said air circulating passageway, and a brine pump having conduit connections for circulating brine from the bottom of said tank and downwardly through said heat exchange unit and discharging said brine as a spray at the top of said ice and brine tank.

THORE M. ELFVING.
